(57) **CLAIM**

The ornamental design for a display screen or portion thereof with graphical user interface as shown and described.

DESCRIPTION

1. Display screen or portion thereof with graphical user interface

1.0 : Front

1.1 is a front view of a display screen or portion thereof with graphical user interface showing our new design; the outer broken lines in the figure show a display screen or portion thereof, and form no part of the claimed design; the other broken lines in the Figure show portions of the graphical user interface that form no part of the claimed design.
